ELECTROLYTIC OXIDATION OF QUINOLINE TO QUINOLINIC ACID

John B. Conn, Westfield, N. J., assignor to Merck & Co., Inc., Rahway, N. J., a corporation of New Jersey

**No Drawing. Application January 5, 1946, Serial
No. 639,425. In Canada March 20, 1942**

2 Claims. (Cl. 204—78)

2

This invention relates to processes for the electrolytic oxidation of pyridine derivatives to their corresponding carboxy acids; and the present application is a continuation-in-part of my pending application Serial No. 418,013, filed November 6, 1941, now abandoned.

The oxidation-reduction effect of electrolysis is well known, but hitherto there has been relatively little application of the principles of electrolysis to pyridine derivatives.

The only reported application of electrolytic oxidation to pyridine derivatives is that of Yokoyama (Bull. Chem. Soc., Japan, 7, 69-72) who oxidized α -picoline in dilute sulfuric acid medium at a lead dioxide anode, using uniform current density of 5.0 amperes per square decimeter. Yokoyama reports that the product he obtained contained only about 20-30% picolinic acid together with a number of by-products comprising ammonia, carbon dioxide, and formic acid. He also showed that picolinic acid is easily destroyed at a lead dioxide anode. The large proportion of by-products obtained by Yokoyama indicates the ease with which the pyridyl ring is split.

I have now discovered an improved process for the electrolytic oxidation of pyridine derivatives. My new process has the advantages that splitting of the pyridyl ring is reduced to a minimum, and high yields of the desired product are obtained.

According to my invention, the selected pyridine derivative is oxidized in about 6 to 12 N sulfuric acid medium at a lead anode coated with lead dioxide, and at low current density, preferably under 2 amperes per square decimeter of anode surface. I have found a current density range of from $\frac{1}{2}$ to $1\frac{1}{2}$ amperes per square decimeter of anode surface most satisfactory. During the later portion of the run, the current density is reduced to prevent the destruction at the anode of the pyridine carboxylic acid which has been formed. In some cases, for instance when quinoline is being electrolyzed, it is advisable to use a higher current density at the start of the electrolysis; otherwise there is a tendency for the lead dioxide anode to be reduced during the early part of the electrolysis. It is preferable to start the electrolytic oxidation of the pyridine derivative in about 6 N sulfuric acid medium. During the electrolysis, the concentration of sulfuric acid gradually increases, reaching about 12 N at the end of the oxidation process.

The cell used is of the two-compartment type, an acid resistant diaphragm, which may be of carborundum, an acid-resisting silicate, a glass

cloth, or other material having similar properties, being used to separate the anode compartment from the cathode compartment. The cathode compartment is packed with a porous acid-resisting substance, such as sand, in order to reduce its free volume to a fraction of that of the anode compartment. This compartment is kept filled with 1:1 (by volume) sulfuric acid (i. e. about 18 N acid).

10 The anode used in this cell is of lead coated with lead dioxide by electrolysis for about 2 to 6 hours in about 6 N sulfuric acid; and is about 2.4 square decimeters in surface area per mole of pyridine derivative to be oxidized, and may be 15 of any convenient shape such as a cylindrical sheet, a coil, or a series of plates. This anode is activated before use either by continuous operation for 24 hours in about 6 N sulfuric acid in the presence of a depolarizer such as quinoline, 20 picoline or the like, or by reversing the polarity for five ten-minute intervals when operating at 1 ampere per square decimeter in the absence of such a depolarizer. The anode can also be activated by actual operation in the oxidation process 25 of the present invention, although when thus activated the current efficiency during the initial stages of the oxidation is very low. When the anode has been activated by any of the methods described above, it remains activated and can be 30 used for a number of successive oxidations without further activation.

The cathode may be of any acid-resisting metal such as copper, a highly resistant steel or an alloy (known as chromel) of the composition nickel 61%, iron 23%, chromium 16%. A non-metal, such as graphite, may also be used as a cathode.

During the course of electrolysis, the temperature may be maintained at the desired level by any one of a number of different convenient means such as by means of heating or cooling coils placed directly in the cell, or by pumping the anolyte through a heat exchanger. Stirring of the anolyte is advisable, and this may be accomplished by any convenient mechanical device, or, if desired, by an air jet placed directly in the anolyte.

The following examples illustrate methods of carrying out the present invention, but it is to be understood that these examples are given by way of illustration and not of limitation.

Example 1

The anode compartment of the two compartment cell is charged with a mixture of 96 cc. (1

mol) of β -picoline, 100 cc. of concentrated (93%) sulfuric acid, and 300 cc. of water. The cathode compartment is filled with 1:1 sulfuric acid.

The anolyte is stirred and is maintained at a temperature of 15-20° C. by passing cold water through a heat exchange coil which is placed directly in the anolyte. The current density is set at 1.0 amperes per square decimeter of anode surface until 210 ampere hours per mole of β -picoline have been consumed. The current is then reduced to 0.5 ampere per square decimeter of anode surface, and this lower current density is maintained for an additional 30 ampere hours. Toward the end of the run, the anolyte becomes thick with suspended crystals of nicotinic acid hydrogen sulfate. The anode compartment is then emptied, washed out, and refilled with another charge of β -picoline, acid and water, and the anode is immediately returned to service to prevent inactivation.

The anolyte liquor and washings are combined, adjusted to pH 3 with sodium carbonate or sodium hydroxide, and allowed to stand until cool. The nicotinic acid which separates is filtered off. The yield is 90 gms. per mol of β -picoline used. Additional acid may be recovered from the liquor by known methods. As for example, through the copper salt, the total yield is about 88%.

Example II

The anode compartment of the two compartment cell is charged with a mixture of 50 gms. quinoline and 200 gms. of concentrated (93%) sulfuric acid, diluted to 400 cc. with water. The current density is set at 4 to 5 amperes per square decimeter of anode surface until 100 ampere hours per mol of quinoline have been consumed. The current density is then reduced to 1.5 amperes per square decimeter of anode surface for an additional 270 ampere hours per mol of quinoline, and is finally reduced to 0.75 ampere per square decimeter of anode surface for a further 220 ampere hours per mol of quinoline. The temperature during the run is maintained at 65-75° C. by means of a heat exchange coil placed directly in the anolyte. The color of the anolyte, which is originally intensely red, fades during the run to pale orange. The cell is emptied, washed out, and recharged for another run.

The anolyte and anode washings are combined, diluted to 800 cc. with distilled water and adjusted to pH 3 with sodium hydroxide. The quinolinic acid is precipitated as the copper or ferrous salt by the addition of a slight excess of

copper sulfate or ferrous sulfate, and the free quinolinic acid is recovered by known methods. The yield is 117 gms. per mol of quinoline used.

Modifications may be made in carrying out the present invention without departing from the spirit and scope thereof, and I am to be limited only by the appended claims.

I claim:

1. The process for preparing quinolinic acid that comprises charging the anode compartment of a two compartment electrolytic cell, having a lead dioxide coated lead anode, with a mixture of quinoline in about 6 N sulfuric acid, agitating the anolyte and oxidizing the quinoline therein by electrolysis at a current density of 4 to 5 amperes per square decimeter of anode surface for about 100 ampere hours per mole of quinoline, then at a current density of about 1.5 amperes per square decimeter for about 270 ampere hours per mole, and finally at a current density of about 0.75 ampere per square decimeter for about 220 ampere hours per mole, and recovering quinolinic acid thus formed from the electrolyte.

2. The process for preparing quinolinic acid that comprises charging the anode compartment of a two compartment electrolytic cell, having a lead dioxide-coated lead anode, with a mixture of quinoline, about 93% sulfuric acid and water, in the approximate ratio of 50 gm. quinoline, 200 gm. acid, and water to bring the volume to 400 cc., agitating the anolyte and oxidizing the quinoline therein by electrolysis at a current density of 4 to 5 amperes per square decimeter of anode surface for about 100 ampere hours per mole of quinoline, then at a current density of about 1.5 amperes per square decimeter for about 270 ampere hours per mole, and finally at a current density of about 0.75 ampere per square decimeter for about 220 ampere hours per mole, and recovering quinolinic acid thus formed from the electrolyte.
